CONTINUOUS PRINTING METHOD AND
APPARATUS THEREFORRay B. Keller, Erie, Pa., assignor to Hammermill
Paper Company, Erie, Pa., a corporation of
Pennsylvania

Application June 18, 1935, Serial No. 27,147

14 Claims. (Cl. 101—219)

This invention relates to a method and apparatus for successively printing a series of impressions on a continuous web of paper or other printing surface.

One object of this invention is to print continuous parallel rows of impressions on a continuous sheet of paper, which may then be cut longitudinally and/or transversely or, if desired, re-wound to match the first impression on one roll with the first impression on other rolls.

A particular feature of the invention is the use of an endless belt carrying the printing forms which may be easily exchanged for another belt carrying a different set of forms. This endless belt is arranged in loops or spirals so that a plurality of printing forms on the belt can be used for printing simultaneously on the same printing surface. A further object is to provide simple and efficient apparatus for carrying out my invention. Further objects and advantages will be more apparent from the description of one embodiment of my invention which is illustrated in the accompanying drawings, and in which:

Figure 1 is a somewhat diagrammatic side view of an assembly for printing in accordance with my invention.

Figure 2 is a plan view of the apparatus taken on the line 2—2 of Fig. 1.

Figure 3 is a view of an enlarged section of the endless belt used in my apparatus for carrying the printing forms.

Figure 4 is a view of the belt shown in Fig. 3, looking at one edge thereof.

Figure 5 is a plan view of my apparatus shown in Fig. 1, taken on the line 5—5 thereof.

Figure 6 is a cross section of the belt taken on the line 6—6 of Fig. 3, and

Figure 7 is a side elevation of my apparatus taken on the line 7—7 of Fig. 1.

In the drawings, numeral 10 indicates a roll of paper or other material on which it is desired to print a series of impressions in parallel rows. This paper or other material may be of any desired width, depending upon the number of parallel rows to be printed and the respective width of each row. A strip of paper 11 is unwound from this feed roll and passed under a freely rotating guide roll 12, between rolls 13 and 14, between the perforating rolls 15 and 16, and is finally wound up on the roll 17. The roll 13 is preferably provided with a perfectly smooth surface, which may be of suitable yielding material such as rubber, and is simply designed to support the paper so that the impressions carried on the belt 18 may be pressed against the paper by the print-

ing roll 14 to the desired degree. Roll 13 may be adjustable vertically, if desired, to provide means for varying the printing pressure. Belt 18 is an endless belt of any desired construction which may, for example, be made of thin sheet steel 19, 5 having cemented thereto by the layer of adhesive 20 any suitable number of rubber or other printing forms 21. These forms 21 are preferably flexible and have their outer surfaces molded to provide a type or printing face suitable for impressing ink onto the paper surface in the desired formations. The continuous belt 18 is looped around the printing roll 14 being guided by flanges 22 thereon and from the printing roll passes upwardly around pulleys 23, 24 and downwardly again around the printing roll 14. The first loop of the belt 18 around the printing roll should be made at one end of said roll and the second loop of the belt 18, after passing over pulleys 23, 24, is made adjacent the first loop in 10 a groove formed by a second of the set of flanges on the roll 14 thus providing a plurality of loops wound in a spiral about said printing roll. These flanges 22 on printing roll 14 provide grooves just 15 sufficiently deep to receive and guide the endless belt 18 allowing the printing forms 21 to extend out beyond said flanges a sufficient distance to be pressed against the paper surface during the printing operation.

In order to prevent twisting of the continuous belt, pulleys 23, 24 are preferably also provided 30 with flanges 25 and rotatably mounted on the shafts 26 and 27, respectively, which are set at an angle to the axis of roll 14, as shown in Fig. 5, to thus give the belt a lead in accordance with 35 its width. The belt may make any desired number of turns around the printing roll 14 and pulleys 23 and 24 although, as illustrated, the belt is shown with ten loops thereby designed to provide ten parallel rows of impressions on the paper 11. 40 It is apparent, of course, that by properly spacing the spiral loops of belt 18 on the printing roll, the rows of impressions on the paper may be spaced apart to any desired degree.

On the feed side of the roll 14, suitable inking 45 rollers 28 are provided which may, for example, be made of hard rubber and mounted to freely rotate, carrying printers ink therebetween. One of these inking rollers bears directly on each of the loops of the continuous belt and thus provides the necessary material for effecting the impressions on the paper 11. Any known construction of inking device may be used in place of the rollers illustrated. Where the printing is to be carried out by simply impressing a form on a sheet of soft 50 55

material, the inking device may be entirely eliminated.

As belt 18 moves around the printing roll for the last time it is carried upwardly and around the three pulleys 29 on shafts 30. Pulleys 29 may be freely rotatable and, if desired, may be given a lead opposite to the lead of the shafts carrying pulleys 23 and 24. As illustrated, the continuous belt 18 forms ten loops about the three pulleys 29 in a spiral the reverse of that about roll 14 and pulleys 23, 24 so that during this period of travel the belt is brought to a position where it again feeds easily without buckling or twisting on to the printing roll 14. The various shafts and rolls 15 may be conveniently mounted in a single frame 31 although any other available mounting and spacing means may be employed.

Various modifications of my invention may be made and will be readily apparent from the foregoing description. While I have shown ten loops of the belt about the printing roll it is apparent, of course, that any desired number may be employed. A corresponding number of loops may be employed about the pulleys 29 and two or any other desired number of these pulleys may be employed instead of the three shown. The pulleys 29 may also be set at an angle to provide a greater lead than that obtained by the pulleys 23 and 24 so that the belt will pass around them only once or twice before it is again brought back into position for printing. Where a relatively large printing roll 14 is employed the pulleys 23 and 24 may be eliminated and the belt simply wound spiral fashion around the printing roll 14 with the free loop festooned about any desired arrangement of pulleys or sheaves. In such a device the grooves 22 on roll 14 would be also arranged spirally instead of as illustrated.

In the operation of the device illustrated, the rolls 13 and 14 are preferably driven as by the gear 32 at the same peripheral speed as the lineal speed of the paper 11 to obtain a smooth unmarred printing action. Guide rolls and perforating rolls may be either driven or freely rotatable with the paper as is well understood in the art. Heaters or other drying means may also be provided to dry the ink before the printed web is wound up to eliminate sticking and rotary cutters may be employed to slit the material lengthwise if desired.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

- 60 1. A method of printing a plurality of parallel rows of impressions comprising passing a plurality of loops of an endless belt carrying printing forms into contact with a surface to receive said impressions.
- 65 2. A method of printing a plurality of parallel rows of impressions comprising inking printing forms carried by an endless belt, and passing a plurality of loops of said belt into contact with a surface to receive said impressions.
- 70 3. A method of printing a plurality of parallel rows of impressions comprising inking printing forms carried by an endless belt, and passing a plurality of loops of said belt into contact with a continuous sheet of paper like material and

moving said material at substantially the same speed as said endless belt.

4. A method of printing a plurality of parallel rows of impressions comprising passing a plurality of loops of an endless belt carrying printing forms spirally about a roll and moving a surface to receive said impressions into contact with the belt carried by said roll. 5

5. A method of printing a plurality of parallel rows of impressions comprising passing a plurality of loops of an endless belt carrying printing forms spirally about a roll, inking the forms carried by said roll and moving a surface to receive said impressions into contact with said inked forms. 15

6. A method of printing a plurality of parallel rows of impressions comprising passing a plurality of loops of an endless belt carrying printing forms spirally about a roll with one of said loops larger than the others and being festooned 20 in a spiral separate from the aforementioned spiral and in reverse direction thereto and moving a surface to receive impressions into contact with the loops of said belt carried by the roll. 25

7. Apparatus for printing a plurality of parallel rows of impressions comprising an endless belt carrying a succession of printing forms spirally looped about a roll and means for passing a surface to receive said impressions into contact with the forms carried by said roll. 30

8. Apparatus for printing a plurality of parallel rows of impressions comprising a roll, means for passing a plurality of loops of an endless belt carrying printing forms spirally around said roll, means for inking the forms on said loops, 35 and means for passing a surface to receive impressions into contact with said inked forms. 45

9. Apparatus for printing a plurality of parallel rows of impressions comprising a roll, means for passing a plurality of loops of an endless belt 40 carrying printing forms spirally around said roll, one of said loops being larger than the rest, means for passing said larger loop in a separate spiral removed from and in reverse direction to the spiral about said roll, and means for moving a surface to receive impressions into contact with the loops about said roll. 55

10. Apparatus for printing a plurality of parallel rows of impressions comprising a pair of co-operating oppositely rotatable rolls, means for passing a plurality of loops of an endless belt carrying printing forms spirally about one of said rolls, and means for passing a sheet of material to receive said impressions between said rolls. 60

11. Apparatus for printing a plurality of parallel rows of impressions comprising a roll, a series of pulleys, an endless belt carrying a succession of printing forms, said belt being spirally wound about said roll and said pulleys, with the loops formed between the beginning and ending of said spiral passing over other pulleys, and means for passing a sheet of material to receive impressions into contact with the printing forms carried by said roll. 65

12. Apparatus for printing a plurality of parallel rows of impressions comprising a roll, a series of pulleys, an endless belt carrying a succession of printing forms, said belt being spirally wound about said roll and said pulleys, with the loops formed between the beginning and ending of said first mentioned spiral wound in a reverse spiral about a second set of pulleys, and means for passing a sheet of material to receive 70 75

impressions into contact with the printing forms carried by said roll.

13. Printing apparatus for printing a plurality of rows of impressions comprising an endless belt having a plurality of printing forms thereon, means for supporting a plurality of loops of said belt, and means for passing a surface to receive impressions into contact with forms on said loops.

14. A method of printing a plurality of rows of impressions on a strip of material and parallel to said strip, comprising conducting a series of printing forms successively into contact with different laterally extending portions of said strip, and moving said forms in the same direction as said strip at the time of contact therewith.

RAY B. KELLER.
